[57] CLAIM

The ornamental design for a mouthpiece for resuscitation, as shown and described.

DESCRIPTION

FIG. 1 is a bottom plan view of a mouthpiece for resuscitation showing my new design;

FIG. 2 is a side elevational view thereof, the opposite side elevational view being a mirror image of that shown;

FIG. 3 is a top plan view thereof;

FIG. 4 is an end elevational view thereof, the opposite end elevational view being a mirror image of that shown;

FIG. 5 is an enlarged sectional view taken along the line 5—5 of FIG. 3; and

FIG. 6 is an enlarged sectional view taken along the line 6—6 of FIG. 3.

Fig. 1.

Fig. 2.

Fig. 3.

Fig. 4.

FIG. 5.

FIG. 6.
